SHUTTLE CHECK FOR LOOMS

Elliot A. Santon, Worcester, Mass., assignor to
Crompton & Knowles Loom Works, Worcester,
Mass., a corporation of Massachusetts

Application February 1, 1946, Serial No. 644,770

2 Claims. (CL 139—185)

This invention relates to improvements in shuttle checks for looms, of the type shown in my co-pending application Serial No. 609,565 filed August 8, 1945, and it is the general object of the invention to provide a shuttle check including a friction member so controlled that it moves through a distance considerably greater than the displacement of the shuttle binder and thereby exerts a large checking force on the shuttle.

Heretofore I have proposed a shuttle check mechanism for a floating binder constructed with a part thereof connected to one end of a strap the other end of which is attached to a spring member. Stationary friction surfaces between the ends of the strap resist movement of the latter as the binder moves forwardly during boxing of the shuttle. In that construction the amount of motion of the strap along the friction surface, and the distortion of the spring, is no greater than the forward motion of the binder.

It is an important object of my present invention to provide a shuttle check in which the strap is required to move a distance along its friction surface considerably in excess of the distance through which the binder is displaced by the shuttle. This result I attain as set forth hereinafter by fastening one end of the strap to a stationary part of the lay so that it can be engaged by a forwardly extending arm or the like on the binder and caused to have a motion along the friction surface greater than the binder motion as the shuttle is boxed. The arm or the like fastened to the binder acts somewhat in the capacity of a movable pulley, wherein motion of a strap or belt is approximately double the motion of the pulley.

It is another object of the invention to provide means for adjusting the position of the fixed end of the strap along the lay so that the shuttle retarding effect of the shuttle check can be varied.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a plan view of one end of a loom lay showing a shuttle box provided with a binder and check therefor constructed according to my present invention, and wherein the binder is in normal checking position.

Fig. 2 is a view similar to a portion of Fig. 1, but showing the shuttle boxed and the binder in its forward position.

Figs. 3 and 4 are vertical sections on lines 3—3 and 4—4, respectively, Fig. 1, looking to the left, and:

Fig. 5 is an enlarged view on line 5—5, Fig. 1 looking to the right.

Referring particularly to Figs. 1 and 2, I have shown a loom lay end 10 having a shuttle box B thereon provided with a floor plate 11 and a rear vertical wall or box back 12. The front of the shuttle box is formed by the floating shuttle binder 13. As shown in Fig. 1 a protector finger 14 engages the inner or left end 15 of the binder. The finger 14 operates in the usual manner and exerts a rearward force on the left end of the binder tending to move the latter toward the wall 12. A guide 16 is secured to the lay and receives the left end of the binder and limits forward movement of the latter in a direction away from the wall 12.

10 The binder comprises a front steel strip 20 to which is secured a block of wood 21 held in position on the strip 20 by bolts 22. A shuttle engaging friction member, made for instance of leather and indicated at 23, has its left end, see Fig. 1, secured to the steel strip 20 at 24. The greater part of the length of member 23 may be glued or otherwise secured to the wooden block 21.

As shown in Fig. 1 the right end of the steel strip 20 is bent forwardly as at 25 and a steel angle 26 is welded thereto to define a horizontal slot 27 extending transversely of the shuttle box. A pin 28 extends through the slot 27 and guides the binder so that the latter can move forwardly and backwardly but is restricted as to longitudinal movement in the direction of the length of the shuttle box.

40 A bracket 30 is bolted as at 31 to the lay end and has a vertical wall 32 in front of the rear wall 12 and extending along the lay end 10. Integral with the wall 32 is a horizontal forwardly projecting shelf 35 from which depend right and left arcuate friction arms 36 and 37, respectively. As shown more particularly in Fig. 5 a bolt 40 extends downwardly through the plate 35 and is 45 tapped into the upper end of a stud 41 the enlarged head 42 of which at the upper end thereof is held in tight frictional engagement with the under surface of the shelf 35 by bolt 40. The stud has a depending reduced shank 43 to the lower end of which is secured a collar 44 as at 45. A nut 46 is made integral with the lower end of the stud 41 and together with the bolt 40 provides means for securing the stud 41 to the shelf in adjusted angular position.

55 A movable strap holder 50 has a vertical wall

51 integral with a horizontal foot 52 which is rotatably mounted on the shank 43 and supported by the collar 44. A coil spring 55 surrounds the stud 41 and has the upper end thereof extending into the head 42 while the lower end thereof is bent outwardly to engage a part of the vertical wall 51 as shown for instance in Fig. 1. The effect of the spring is to turn the strap holder 50 in a clockwise direction as viewed in Fig. 1, and the force exerted by the spring can be varied by reason of the angular adjustment of the stud 41 already described. A friction strap of leather or the like indicated at 56 has one end thereof secured as at 57 to holder 50, and extends along friction arms 36 and 37.

The matter thus far may be substantially the same as that set forth in my prior Patents Nos. 2,045,967 and 2,390,963.

In carrying my present invention into effect I provide the binder with a forwardly extending arm 60 the front part of which is rounded as at 61 to engage that part of the strap to the left of the friction arm 37. The left end of the strap is secured to a bolt 62 extending between top and bottom arms 63 and 64, respectively, on bracket 30. These latter arms are slotted as at 65, and a nut 66 and lock washer 67 hold the bolt 62 in adjusted position along the slots.

Ordinarily spring 55 holds the strap taut and keeps the binder in checking rear position, see Fig. 1, with arm 60 against a stop screw 70 on bracket 30. When the shuttle enters the box the binder is moved forwardly and as the arm 60 and rounded surface 61 advance they draw the strap to the left around the friction surfaces 36 and 37. The amount of motion of the strap along these friction surfaces is greater than the amount of forward motion of the binder due to the fact that the left end of the strap as viewed in Fig. 1 is fixed with respect to the lay by the anchor bolt 62. The spring is therefore placed under a stress which is proportionally greater than that which would exist if the strap were fastened to the binder as in the aforesaid Patent No. 2,390,963. The rounded part 61 acts somewhat in the nature of a movable pulley in that it requires the strap to move farther than does arm 60, and for this reason there is an increased checking effect on the shuttle. The amount by which motion of the strap exceeds forward motion of the binder will of course depend upon the location of the lay carried anchor bolt 62 for the left end of the strap. If for instance this anchor should be moved to the right of the position shown in Fig. 1 and be close to the arm 60, the motion of the strap will be approximately double that of the binder. By providing for the adjustment of the anchor along the lay it is pos-

sible to vary the increase of strap motion over the binder motion.

From the foregoing it will be seen that I have provided a simple form of shuttle check wherein a strap is caused to move along a friction surface for a distance greater than the displacement of the binder. This result is accomplished by having one end of the strap fixed with respect to the lay and engaging the strap at a point between its ends by a part carried by the binder. The amount by which the strap motion exceeds the binder motion can be varied depending upon the position of the strap anchor along the lay, but in each of these positions the strap will be required to move farther than the binder moves when the shuttle enters the box. The excess of motion on the part of the strap over the motion of the binder not only gives an additional frictional resistance to entry of the shuttle into the box, but increased resistance is also offered by spring 55.

Having thus described my invention it will be seen that changes and modifications may be made therein by those skilled in the art without departing from the spirit and scope of the invention and I do not wish to be limited to the details herein disclosed, but what I claim is:

1. In shuttle checking mechanism for a loom having a lay provided with a shuttle binder, a shuttle checking strap having one end thereof resiliently mounted with respect to the lay for movement relatively to the latter, holding means for the other end of the strap, friction means on the lay engaging the strap intermediate the ends thereof, a member on said binder engaging said strap between said friction means and holding means and moved by the binder at the time of shuttle boxing in a direction to cause said strap to move along said friction means, and adjusting means to secure said holding means to the lay at different distances from said friction means.

2. In checking mechanism for a loom having a lay and a shuttle binder thereon moved laterally of the lay at the time of shuttle boxing, a shuttle checking strap, means mounting one end of said strap resiliently with respect to the lay, anchor means connecting the other end of the strap to the lay, friction means fixed with respect to the lay engaging the strap between the ends thereof, means on the binder engaging the strap between said anchor means and said friction means causing the strap to move along said friction means when the binder moves laterally of the lay incident to shuttle boxing, and means to secure said anchor means to the lay in any one of a plurality of positions at different distances from said friction means.

ELLIOT A. SANTON.
